UNITED STATES PATENT OFFICE

158,911

RUBBER BOOT OR SIMILAR ARTICLE

Masato Suyama, Denver, Colo.

Application July 18, 1949, Serial No. 3,984

Term of patent 14 years

(Cl. D7—4)

To all whom it may concern:

Be it known that I, Masato Suyama, a citizen of the United States, residing at Denver, State of Colorado, have invented a new, original, and ornamental Design for Rubber Boots or Similar Articles, of which the following is a specification, reference being had to the accompanying drawing, forming a part hereof.

In the drawing,

Figure 1 is a side elevation of a rubber boot showing my new design, the opposite side presenting substantially the same appearance as the side shown.

Figure 2 is a bottom plan view of the same; and

Figure 3 is a section taken on line 3—3, Fig. 2.

The essential features of my design reside in the sole portion of the rubber boot shown in heavy lines.

I claim:

The ornamental design for a rubber boot or similar article, as shown and described.

MASATO SUYAMA.
